UNITED STATES PATENT OFFICE.

WILLIAM C. STIEFELHAGEN, OF BUFFALO, NEW YORK, ASSIGNOR TO MIDLAND PAPER BOX CO., INC., OF BUFFALO, NEW YORK, A CORPORATION OF NEW YORK.

FASTENER FOR BOXES.

Application filed August 24, 1921. Serial No. 495,072.

To all whom it may concern:

Be it known that I, WILLIAM C. STIEFELHAGEN, a citizen of the United States, residing at Buffalo, in the county of Erie and 5 State of New York, have invented certain new and useful Improvements in Fasteners for Boxes, of which the following is a specification.

This invention relates to new and useful 10 improvements in fasteners for boxes made of paper, or other material, and in which a cover telescopes over the body portion of the box, or a portion thereof.

More particularly, this invention relates 15 to that type of fasteners adapted to be secured to the body-portion of the box and inserted through slits formed in the cover, the portions thereof extending through said slits being bent down against the sides or 20 ends of the cover, as the case may be.

This invention has for its object, to provide a fastener of this type which will guard against the downwardly bent tongue thereof being accidentally bent upwardly or straightened, thus preventing accidental displacement of the cover from the body portion.

The invention consists in the novel construction hereinafter described and particularly defined in the appended claims.

30 The invention is illustrated in the accompanying drawings, in which:—

Fig. 1 is a perspective view of a box equipped with my invention.

Fig. 2 is a perspective view of the body 35 portion of the box.

Fig. 3 is a longitudinal section taken centrally through the box.

Figs. 4 and 5 are perspective views of the 40 fastener showing the retainer or locking portion on the tongue in different positions.

The numeral 1 designates the body portion of a box constructed of pasteboard, cardboard, or similar material, and 2 the cover thereof telescoped over the upper open end 45 of the body portion; boxes of this kind being especially designed for mailing small articles.

Boxes of this kind are invariably constructed of cardboard or similar material, 50 and to the exterior surfaces of this material a similar paper covering is applied to give the box a neat and finished appearance.

55 3 designates my improved fastener, which comprises a body portion 4 having an up-

standing tongue 5 projecting from one edge thereof, the body portion being provided with pointed securing prongs 6 at opposite ends thereof, which are stamped from said body portion and bent at right angles thereto so that they may be pressed into and through the side or end walls of the body portion and be clenched on the inner or outer sides of said side walls, as may be desired, to secure the fastener to said body portion. While I have shown pointed securing prongs, any other means may be provided for securing the fastener to the body portion of the box.

The cardboard from which the cover 2 is 70 formed is provided with slits 7, which, however, are concealed by the paper covering material, so that when applying the cover to the body portion of the box, the upstanding tongues 5 of the fasteners are entered in 75 the slits 7 in the cardboard portion of the cover and forced through the paper covering material. These tongues therefore extend upwardly through the slits 7 and the paper covering material and are adapted to 80 be bent over the ends or sides of the cover, as the case may be. To prevent these bent ends from being accidentally bent back or straightened when in transit, I provide each of the tongues with an outwardly-directed 85 pointed prong 8, which is stamped from said tongue. When said tongues are bent over the sides or ends of the cover and pressed in contact therewith, the prongs 8 are forced into the cover so that a direct 90 outward pull on the bent portions of the tongues will be required in order to straighten the tongues so as to permit the cover to be removed from the body portion. These pointed prongs I term locking or retainer 95 prongs since they prevent accidental displacement of the cover when forced thereinto.

The fasteners may be used as shown in Fig. 4, in which the retainer or locking 100 prong 8 on the tongue is merely stamped in said tongue by two V-shaped downwardly converging slits 9. This permits the cover to be easily slipped onto the body portion of the box without making the slits in the 105 cover any wider than the thickness of the tongue, and after the cover is slipped over the upstanding tongues, the prong may be forced outwardly, as shown at the left in Fig. 3, and the tongue being then bent over 110

the side or end of the cover, as shown at the right in Fig. 3, whereupon the locking or retainer prong 8 will enter the side or end of the cover, as the case may be, and lock the tongue in place. With the tongue and locking or retainer prong thus arranged, it will require both outward and upward pressure on the tongue in order to straighten the same, and therefore in shipping, assurance will be had that the bent tongue will retain the cover on the body portion of the box.

If desired, the fastener may be utilized, as shown in Fig. 5, in which position the retainer or locking prong 8 is bent from the tongue, but when so used it may be found necessary to slightly widen each slit 7 in the cover at a point centrally between its ends, to prevent bending of the prong while placing the cover on the body portion.

Having thus described my invention, what I claim is:—

1. In combination with the body portion of a box and its cover having a slit therein, of a fastener secured to said body portion and having an upstanding tongue adapted to pass through the slit of said cover, said tongue being bent outwardly and downwardly into engagement with the cover and

having means thereon adapted to prevent accidental straightening of said tongue when in contact with said cover.

2. In combination with the body portion of a box and a cover having a slit therein, a fastener secured to one of the upright walls of said body portion and having a bendable tongue passed through the slit of said cover, said tongue being provided with an outwardly-projecting prong adapted to be forced into the cover when bending said tongue outwardly and downwardly against the side or end of said cover.

3. In combination with the body portion of a box and its cover having a slit therein, a fastener secured to said body portion having an upstanding bendable tongue provided with a V-shaped slit, the metal between the V-shaped slit being adapted to be bent outwardly after said cover is slipped onto said body portion so as to form a pointed prong on said tongue, said tongue being adapted to be bent outwardly and downwardly against the side of the cover with said pointed prong forced into the side or end of said cover.

In testimony whereof I affix my signature.

WILLIAM C. STIEFELHAGEN.
